STRAND OF BEADS FOR A CURTAIN ELEMENT OR THE LIKE

Irving Levine, 9171 Gazette Ave.,
Chatsworth, Calif. 91311

Filed Aug. 16, 1971, Ser. No. 172,374

Term of patent 14 years

Int. Cl. D6—10

U.S. Cl. D6—205

Fig. 1.

Fig. 2.

Fig. 3.

FIG. 1 is a perspective view of a strand of beads for a curtain element or the like showing my new design;

FIG. 2 is a top view of the said strand taken along line 2—2 of FIG. 1 hereof; and

FIG. 3 is a horizontal cross-sectional view of a bead comprising said strand along line 3—3 of FIG. 1 hereof.

I claim:

The ornamental design of a strand of beads for a curtain element or the like, as shown and described.
